(57) **CLAIM**

The ornamental design for the fence pipe plumb level, as shown and described.

DESCRIPTION

FIG. 1 is a perspective view of a fence pipe plumb level showing a first embodiment

FIG. 2 is a perspective view from the opposite side of that shown in FIG. 1;

FIG. 3 is a side elevation thereof;
FIG. 4 is a top plan view thereof;
FIG. 5 is a cross-section view taken along line 5-5 of FIG. 4;
FIG. 6 is a bottom plan thereof;
FIG. 7 is an end view thereof;
FIG. 8 is an end view thereof from the opposite side of that shown in FIG. 7;
FIG. 9 is a perspective view showing the article in use;
FIG. 10 is a perspective view of a second embodiment;
FIG. 11 is a perspective view from the opposite side of that shown in FIG. 10;
FIG. 12 is a bottom plan view thereof;
FIG. 13 is a side elevation view thereof;
FIG. 14 is a top plan view thereof;
FIG. 15 is a cross-section view taken along the line 15-15 of FIG. 14;
FIG. 16 is an end view thereof;
FIG. 17 is an end view from the opposite side of that shown in FIG. 16;
FIG. 18 is a perspective view of a third embodiment;
FIG. 19 is a perspective view from the opposite side of that shown in FIG. 18;
FIG. 20 is a side elevation view;
FIG. 21 is a top plan view thereof;
FIG. 22 is a cross-section view taken along the line 22-22 of FIG. 21;
FIG. 23 is a bottom plan view thereof;
FIG. 24 is an end view thereof;
FIG. 25 is an end view from the opposite side of that shown in FIG. 24;
FIG. 26 is a perspective view of a fourth embodiment;
FIG. 27 is a perspective view from the opposite side of that shown in FIG. 26;
FIG. 28 is a side elevation view;
FIG. 29 is a top plan view thereof;
FIG. 30 is a cross-section view taken along the line 30-30 of FIG. 29;
FIG. 31 is a bottom plan view thereof;
FIG. 32 is an end view thereof; and,
FIG. 33 is an end view from the opposite side of that shown in FIG. 32.

The broken lines shown in the figures are for the purpose of illustrating environment only and form no part of the claimed design.
